United States Patent Office

Des. 203,800
Patented Feb. 22, 1966

203,800

SIGN HOLDER

Sander Charles Nestegard, White Bear Lake, Minn.,
assignor to Elaine A. Nestegard

Filed June 21, 1965, Ser. No. 85,830

Term of patent 14 years

(Cl. D1—3)

FIG. 1

I claim:

The ornamental design for a sign holder, as shown and described.
